METHOD OF PRODUCING MANIFOLDING MATERIAL

Filed Sept. 19, 1931

UNITED STATES PATENT OFFICE

1,985,062

METHOD OF PRODUCING MANIFOLDING MATERIAL

John Q. Sherman, Dayton, Ohio, assignor to The Standard Register Company, Dayton, Ohio, a corporation of Ohio

Application September 19, 1931, Serial No. 563,823

4 Claims. (Cl. 282—12)

This invention relates to the manufacture of manifolding material, and particularly of tabbed material whereby finger tabs and cutouts are provided in succeeding sheets of transfer material interposed between the record strips to facilitate the separation of detached portions of the record and transfer material.

The present invention is a further development and improvement in the process of manufacture 10 of the tabbed manifolding material shown and described in applicant's co-pending applications for Letters Patent Serial No. 435,213 filed Mar. 12, 1930; Serial No. 437,655 filed Mar. 21, 1930; Serial No. 444,724, filed Apr. 16, 1930, and Serial 15 No. 551,724 filed July 18, 1931.

While for illustrative purposes the present invention has been shown applied only to finger tabs of semi-circular form, it is to be understood that the present invention and method of production are applicable to finger tabs of various 20 shapes and proportions such as shown in the above identified pending applications for patents.

It has been found in the manufacture of tabbed manifolding material wherein the material is 25 scored or weakened on transverse lines at spaced intervals for subsequent sub-division into succeeding sheets, that the continuation of the score lines or weakening lines across the area of the tabs results in the tabs being accidentally torn off. It is also found that because of the weakened line across the base of the tab, the tab 30 is quite likely to become displaced or reversed intermediate the record sheets thus leaving a vacancy in one sheet and doubling the thickness 35 of the transfer material commensurate with the area of the tab in the adjacent sheet which also, due to reversal of the tab, prevents transfer over such area.

The object of the present invention is to over- 40 come the difficulty of manufacture heretofore experienced, and to provide a method of providing tabbed stationery in which the tab will be of maximum strength and unweakened or unaffected by the scoring of the material, and wherein 45 the tab will be caused to maintain its normal relation in the plane of the transfer strip during the feeding and writing operation.

A further object of the invention is to provide 50 an improved method of manufacture which will be economical, and which will not involve difficulties of manufacturing operation nor the necessity for special equipment other than that heretofore employed in the manufacture of similar material.

55 With the above primary and other incidental

objects in view as will more fully appear in the specification, the invention consists of the features of construction, the parts and combinations thereof, and the mode of operation, or their equivalents, as hereinafter described and set forth in the claims.

Referring to the accompanying drawing, Fig. 1 is a perspective view of a portion of a strip of transfer material in which the spaced finger tabs and cutouts have been formed preparatory to 10 the transverse scoring or perforation upon spaced division lines. Fig. 2 illustrates the reversely folded finger tab, the fold lines of which are in slightly spaced relation with the transverse division lines of scoring or perforation and hence not 15 intersected thereby. Fig. 3 is a perspective view of a packet of superfolded manifolding material including interposed tabbed transfer strips manufactured in accordance with the present method. Fig. 4 is a detail view of a portion of the strip 20 of transfer material removed from the packet and illustrating the effect of refolding of the finger tabs simultaneously with the folding of the strip upon the transverse division lines. Fig. 5 is a perspective view illustrative of the method 25 of detaching packets of superposed leaves from the strips of manifolding material. Fig. 6 is a similar view illustrating the manner of separating the detached leaves of record and transfer material.

Like parts are indicated by similar characters of reference throughout the several views.

Briefly stated the present method of production 30 consists in initially cutting the strip of transfer material at spaced intervals to form the requisite finger tabs and corresponding cutouts and folding the tongue or tab thus formed reversely onto the strip of material, and thereafter transversely scoring or perforating the strip of transfer material in slightly offset relation with the fold line 40 of the tab or tongue so that the latter is not intersected or weakened and after returning the preliminarily folded tab to its normal position within the cutout, the strip is reversely folded into zig-zag formation upon succeeding weakened 45 transverse score or division lines which folds now intersect the tab, causing the tab to lie in the plane of the strip but without being weakened or perforated.

Referring to the drawing, 1 is the strip of 50 transfer material and 2—2 are tabs or tongues of material cut therefrom at spaced intervals agreeing substantially with the spacing of the transverse division lines upon which the strip is to be subsequently divided into succeeding sheets. 55

These tabs 2—2 are reversely folded upon the line 3, as shown in Fig. 2, and the strip 1 is then transversely scored, perforated, or otherwise weakened upon transverse division lines 4—4 which are slightly offset relative to the fold line 3 of the tab which forms the base thereof. Hence the score or perforation lines 4 do not intersect the tabs 2 but do intersect the cutout 5 from which the tab has been removed. Subsequently to the scoring or weakening of the strip upon the transverse division lines 4, the tabs 2 are returned to their normal position in the plane of the strip, and the strip including the tab is then folded reversely upon succeeding transverse division lines 15 4, the fold lines of the strip intersecting the tabs 2 upon the fold line 6 thereof. Thus the tab is caused to lie in the plane of the strip beyond the fold lines thereof, but the tab is maintained of maximum strength throughout, and the fold line 20 of the tab not having been previously weakened, the tab will maintain its position and is not so likely to become displaced or reversed between the strip before reaching the writing position.

The tabbed strips of transfer material 1, are assembled in interleaved relation between superposed strips 7—7 of record material and is shown particularly in Fig. 3 the superposed strips being collectively folded to and fro coincident with the registering score lines 8 of the record strips and the lines 6 of the transfer strip.

After use the packets of used sheets are simultaneously detached from the supply strips by grasping the sheets and tearing them transversely upon the registering division lines 8 and 6 of the respective record and transfer strips, after which the detached sheets are easily and quickly separated from each other by collectively grasping the record sheets within the area of the cutouts 5 of the interposed transfer sheet and simultaneously grasping the protruding tabs 2 of such transfer sheets at the opposite margins of the packet and pulling the respective sheets in opposite directions as is illustrated in Fig. 6.

As an alternative construction, the scoring rule, 45 perforating device or other means for effecting the scoring or delineation of the division lines 4, may be interrupted or cut away coincident with the position of the tabs 2 thereby terminating the division lines at the margins of the cutout 5 and leaving the tabs 2 unscored and unweakened.

From the above description it will be apparent that there is thus provided a device of the character described possessing the particular features of advantage before enumerated as desirable, but which obviously is susceptible of modi-

fication in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. The herein described method of producing tabbed transfer material, including cutting a strip of material to form tabs at spaced intervals, folding the tabs backwardly upon the strip, 20 transversely scoring the strip of material for subsequent division upon lines offset beyond the fold line of the tab, unfolding the tab and re-folding the tab and sheet upon a transverse line substantially co-incident with the score line.

2. The herein described method of producing manifolding transfer material, including forming therein a series of integral tabs at spaced intervals, displacing the tabs, scoring the material for transverse division on lines intersecting the area from which the tabs have been displaced, and subsequently folding the material including the tab on lines substantially coincident with the score lines.

3. The herein described method of producing manifolding transfer material, including forming in a strip of transfer material a succession of integral tabs at spaced intervals, displacing the tabs and providing transverse division lines on which the strip is divisible into sheets intersecting the areas from which the tabs were displaced but in non-intersecting relation with the tabs.

4. The herein described method of producing manifolding transfer material, including forming in the strip a succession of integral tabs at spaced intervals, displacing the tabs therefrom and providing transverse division lines upon the strip in offset relation with the bases of the tabs whereby the material of the tabs will not be intersected thereby and returning the tabs to substantially original relation with the strip.

JOHN Q. SHERMAN.
